UNITED STATES PATENT OFFICE.

ORLANDO W. ALDRICH AND SOLOMON M. HALL, OF COLUMBUS, OHIO.

FIRE-EXTINGUISHER.

SPECIFICATION forming part of Letters Patent No. 514,534, dated February 13, 1894.

Application filed August 19, 1893. Serial No. 483,497. (No model.)

To all whom it may concern:

Be it known that we, ORLANDO W. ALDRICH and SOLOMON M. HALL, citizens of the United States, residing at Columbus, in the county of Franklin and State of Ohio, have invented certain new and useful Improvements in Fire-Extinguishers; and we do hereby declare the following to be a full, clear, and exact description of the invention, such as will enable others skilled in the art to which it appertains to make and use the same.

Our invention relates more particularly to vessels or reservoirs for containing solutions of fire extinguishing compounds, and especially to such as are provided with a pump for throwing the solution onto a fire.

Some of the solution compounds employed to extinguish fires are of a volatile nature, and when allowed to stand for any considerable period in vessels as ordinarily constructed lose much of their virtue. To overcome this difficulty we propose to make the vessel as air or gas-tight as possible. Another difficulty experienced with apparatus of this kind consists in the settling of large quantities of solids upon the bottom of the vessel which chokes the outlet to the pump and greatly interferes with or wholly obstructing the operation of that instrument. A feature of our invention, therefore, consists in the provision of means whereby the contents of the vessel (and especially such solids as may have settled at the bottom thereof) may be agitated and dislodged, thereby permitting a free flow of the solution to the pump. When the substances employed in the extinguishing solution are of a corrosive nature, it is important that they be kept from contact with the parts of the pump as much as possible; and our invention includes the provision of devices whereby the pump may be readily and conveniently disconnected for cleaning the same after use without losing or exposing the contents of the reservoir.

The several features of our improvements are illustrated in the accompanying drawings in which—

Figure 1 is a sectional view of an apparatus embodying our improvements having a

single pump. Fig. 2 is a sectional view of a 50 screw-threaded collar for connecting the upper end of the pump to the agitator pipe.

The vessel or reservoir 1 may be of any form but the ordinary cylindrical or barrel form is preferred; and its upper end, instead of being 55 provided with a large removable cover as usual, will be tightly closed except at the middle where there is a small opening 2 through which water and the extinguishing compound may be supplied. This small opening will be 60 closed by a screw cap 3 having a suitable air or gas-tight packing. The pump 4 which is placed on the outside of the vessel is screw-threaded at its lower end so as to turn into and be connected with the projecting end of 65 the strainer pipe 7. The upper end of the pump has two short outlet pipes 5 and 6 to one of which is connected the hose pipe 9 while the other is connected, by means hereinafter described, to a pipe 10 that extends 70 through the top to the bottom of the vessel. The means for connecting the pump with the pipe 10 consists of a screw-threaded collar 15, as shown, so that when said collar is turned up on the pipe 10 it is turned off the outlet 75 pipe 6. The collar 15 will preferably contain a stop-cock 13. The strainer pipe 7 preferably extends entirely across the bottom of the vessel and is secured tightly in opposite sides thereof so as to afford a more firm support for 80 the pump. The lower end of the pipe 10 terminates in a nozzle 11 which is so arranged as to throw a stream onto the strainer or onto the bottom of the vessel when liquid is forced down through said pipe and thus quickly and 85 thoroughly dislodge and agitate substances that may have settled there.

A stop-cock 12 is provided in the hose pipe or in the short pipe 5 and when this is closed and the stop cock 13 opened the solution may 90 be pumped out of the vessel and back again through the agitator pipe.

To remove the pump for the purpose of cleaning it of corrosive or obstructing substances it is only necessary to close the cock 95 14 on the outer projecting part of the strainer pipe, turn the collar 15 off the pipe 6 and unscrew the lower end of the pump. The cock

14 should be kept closed except when it is desired to agitate the contents of the vessel or to use the apparatus in case of fire.

If two or more pumps are employed on one vessel they will preferably be connected with the same strainer and the agitator pipes may terminate in the same nozzle or outlet.

When the apparatus is large and designed for public or extensive use the vessel may be supported upon a wheeled carriage of any suitable construction.

To use the apparatus at a fire it is only necessary to close the cock 13, open the cocks 12 and 14 and take off the screw cap 3 when the pump or pumps may be worked as usual.

Among the numerous advantages of our apparatus are: first, it is simple and inexpensive in construction; second, it is very durable; third, no special knowledge or skill is required to operate it and keep it in readiness for use.

What we claim, and desire to secure by Letters Patent, is—

1. In combination with a vessel adapted to contain a fire extinguishing liquid, of a pump arranged on the outside thereof having its inlet end communicating with the interior of the vessel and having two outlets, one communicating with the interior of the vessel near its bottom, and the other adapted to be

connected with a hose, the said outlets being provided with stop cocks, substantially as described.

2. In combination with a vessel adapted to contain a fire extinguishing liquid, a projecting inlet for said vessel screw-threaded at its end, a stop cock 14 in said inlet, an agitator pipe projecting through and rigidly connected with the vessel and having its end screw-threaded, a stop cock 13 for said pipe, a pump cylinder screw-threaded at its lower end so as to be detachably connected with the screw-threaded outlet pipe and having a screw-threaded outlet at its upper end, and a collar 15 threaded to engage the threads of the outlet at the upper end of the pump and those of the agitator pipe so that the said outlet and agitator pipe may be detachably joined, whereby the pump may be readily removed from the vessel without disturbing the agitator pipe, substantially as described.

In testimony whereof we affix our signatures in presence of two witnesses.

ORLANDO W. ALDRICH.
SOLOMON M. HALL.
